SMOKING APPLIANCE

Ray Glen Thomas, Ogden, Utah

Application June 22, 1936, Serial No. 86,666

4 Claims. (Cl. 131—175)

This invention relates to a smoking appliance adapted for use as a holder for cigars and cigarettes.

The primary object of the present invention is to provide a device of this character which is simple and durable in construction, efficient in use, and adapted to confine the cigar or cigarette when it is being smoked, so as to prevent the ashes from being scattered.

10 Other objects of the present invention is to provide a device of the above kind which is easy and convenient to use, which is so constructed as to effectively hold the cigar or cigarette in position for being smoked, and in which the cigar or cigarette may be readily positioned or from which said cigar or cigarette may be readily removed.

Other objects and features of the present invention will become apparent from the following description when considered in connection with the accompanying drawings, in which:

Figure 1 is a view of an embodiment of the present invention, partly in side elevation and partly in longitudinal section.

25 Figure 2 is an enlarged end elevation looking toward the right of Figure 1.

Figure 3 is an enlarged transverse section on line 3—3 of Figure 1.

Figure 4 is a side elevational view of another embodiment of the present invention.

Figure 5 is an enlarged transverse section on line 5—5 of Figure 4.

Figure 6 is a view of the device shown in Figure 4, partly in elevation and partly in longitudinal section.

Figure 7 is an enlarged transverse section on line 7—7 of Figure 4.

Figure 8 is a plan view of still another embodiment of the present invention.

40 Figure 9 is an enlarged transverse section on line 9—9 of Figure 8.

Figure 10 is an enlarged transverse section on line 10—10 of Figure 8; and

Figure 11 is a view similar to Figure 6 of the device shown in Figure 8.

Referring in detail to the drawings, a smoking appliance constructed in accordance with the present invention includes a mouthpiece 5 having the usual longitudinal smoke passage or opening 6 and provided in the larger outer end thereof with the usual relatively deep and slightly tapered socket 7 for snug retaining reception of the inner end of the cigar or cigarette to be smoked. Carried by the outer end of the mouthpiece 5, and coaxial with the latter is a tubular

casing 8 adapted to receive and completely confine the cigar or cigarette engaged in the socket 7, the cigar or cigarette being supported in spaced concentric relation to the casing 8. As shown, the casing 8 consists of a tubular member provided with a plurality of longitudinal slots 9 which are relatively wide and are separated by narrow longitudinal strip portions 10, and each of which extends substantially the entire length of such tubular member, as shown. 10 Each of the slots 9 is covered by freely foraminous material such as coarsely woven wire screening 11 capable of retaining ashes although permitting free circulation of air between the cigar or cigarette and the casing and insuring 15 a plentiful supply of air to the burning end of the cigar or cigarette for properly promoting combustion. The outer end of the tubular casing 8 is also closed by a wall or disk 12 which is preferably perforated for further admission 20 of air. At the inner end of the casing 8, the latter is formed with a restricted bore portion 13 which tapers smaller inwardly relatively abruptly and acts as a guide to properly lead the end of the cigar or cigarette into the socket 25 7 of the mouthpiece.

In the embodiment of Figures 1 to 3 inclusive, the mouthpiece 5 and casing 8 are separately formed, and the casing 8 is frictionally telescoped at its inner end onto the outer end 30 of the mouthpiece 5, as at 14, so that these parts are separable to facilitate cleaning thereof and to facilitate removal of the top of the cigar or cigarette from the socket 7. Also, in this embodiment, the end wall or disk 12 is 35 preferably in the nature of a hinged closure releasably held in closed position by a spring catch 15 and hinged as at 16 to swing outwardly and downwardly to open position. By opening this closure, the cigar or cigarette may 40 be inserted in the device without separating the casing and mouthpiece, and ashes may be dumped from the casing when convenient by simply opening this closure.

In the embodiment of Figures 4 to 6 inclusive, 45 the casing 8 is formed in longitudinal sections, and likewise with respect to the outer end portion of the mouthpiece 5 which is formed with the socket 7. One longitudinal section of the casing 8 and of the socketed portion of the 50 mouthpiece 5 are integrally formed with each other and with the body of the mouthpiece 5, while the remaining section of the casing 8 and the remaining section of the socketed portion of mouthpiece 5 are integrally formed with each 55.

other and provide a swinging member hinged at 17 at its inner end to the body of the mouthpiece 5 so that it may be swung upwardly to open position as indicated by dotted lines in Figure 4. This permits ready insertion or removal of the cigarette and ready dumping of the ashes from the holder, and the hinged member is normally yieldingly closed by employing a spring at 17'. Obviously, the cigarette may be engaged in the portion of the socket in that part of the mouthpiece which is integral with the body of the mouthpiece, and when the hinged member is subsequently allowed to close, the inner end of the cigar or cigarette will be firmly held or clamped in place in the socket 7. On the other hand, when the hinged member is swung to the open dotted line position of Figure 4, the butt of the cigar or cigarette will be immediately released. To facilitate swinging of the hinged member to the dotted line open position of Figure 4, said member may be provided at its inner hinged end with a finger-piece 18 upon which downward pressure may be exerted for causing swinging of the said hinged member to open position. A notch 19 may be provided in the adjacent portion of the mouthpiece 5 to provide sufficient clearance for the fingerpiece 18 when so pressed. It will also be noted from Figure 7, that the coacting or adjacent longitudinal edges of the fixed and movable members of the device are cooperatively constructed to provide substantially airtight latch joints 20 along such edges when the hinged member is in closed position. This also provides for strength and durability guarding against relative lateral displacement of the parts when the hinged member is closed.

The device of Figures 8 to 11 inclusive is constructed similar to the device of Figure 4 except that the hinged member is hingedly connected along one of its longitudinal edges with the fixed member of the casing as at 17a, the hinged member being releasably held in closed position by a spring catch 21, and spring hinges being employed at 17a for normally swinging the hinged member to open position upon release of the catch 21. As in the device of Figure 4, the device of Figure 8 has one section of the casing and one section of the socketed portion of the mouthpiece integrally formed, so that when the hinged member is swung open the end of the cigar or cigarette engaged in the socket 7 is released, and so that such end is firmly held or clamped in place when the hinged member is closed.

In the operation of all forms of the invention illustrated, the cigar or cigarette is placed in the casing with its inner end firmly engaged in the socket 7 so that said cigar or cigarette is effectively held or supported within the casing and in spaced concentric relation to the latter. With the casing properly closed after the cigar or cigarette has been lighted and placed in the appliance, the smoke is drawn through the passage or opening 6, air being allowed to enter through the perforations in the end wall or disk 12 and the freely perforated material 11. As ashes fall or are displaced from the end of the burning cigar or cigarette, it is retained in the casing 8 until conveniently and intentionally dumped therefrom.

What I claim as new is:

1. In a device of the character described, the combination of a mouthpiece having a longitudinal smoke passage and provided in its outer end

with a slightly tapered socket adapted for retaining reception of the end of a cigar or cigarette, and a tubular casing carried by the outer end of and coaxial with said mouthpiece, said casing being freely perforated substantially throughout the entire length thereof and having a restricted bore portion near its inner end abruptly tapered inwardly and terminating flush with the outer end of the mouthpiece socket to guide the end of said cigar or cigarette into said socket of the mouthpiece.

2. In a device of the character described, the combination of a mouthpiece having a longitudinal smoke passage and provided in its outer end with a slightly tapered socket adapted for retaining reception of the end of a cigar or cigarette, and a tubular casing carried by the outer end of and coaxial with said mouthpiece, said casing being freely perforated substantially throughout the entire length thereof and having a restricted bore portion near its inner end abruptly tapered inwardly to guide the end of said cigar or cigarette into said socket of the mouthpiece, said tubular casing being frictionally and detachably telescoped at its inner end onto the outer end of said mouthpiece, and an end closure disk for the outer end of said casing, said closure disk being perforated and hinged to swing outwardly and downwardly to open position.

3. In a device of the character described, the combination of a mouthpiece having a longitudinal smoke passage and provided in its outer end with a slightly tapered socket adapted for retaining reception of the end of a cigar or cigarette, and a tubular casing carried by the outer end of and coaxial with said mouthpiece, said casing being freely perforated substantially throughout the entire length thereof and having a restricted bore portion near its inner end abruptly tapered inwardly to guide the end of said cigar or cigarette into said socket of the mouthpiece, said tubular casing being formed in longitudinal sections, the socketed end portion of the mouthpiece also being formed in longitudinal sections, one section of the casing and one section of the socketed portion of the mouthpiece being integral with each other and with the body portion of the mouthpiece, the other section of said casing and the other section of said socketed portion of the mouthpiece being integral with each other and being hinged to the body portion of the mouthpiece, whereby to provide a member for clamping the cigar or cigarette in place when closed and for releasing the cigar or cigarette when opened.

4. In a device of the character described, the combination of a mouthpiece having a longitudinal smoke passage and provided in its outer end with a slightly tapered socket adapted for retaining reception of the end of a cigar or cigarette, a tubular casing carried by the outer end of and coaxial with said mouthpiece, said casing being freely perforated substantially throughout the entire length thereof and having a restricted bore portion near its inner end abruptly tapered inwardly to guide the end of said cigar or cigarette into said socket of the mouthpiece, said tubular casing being formed in longitudinal sections, the socketed end portion of the mouthpiece also being formed in longitudinal sections, one section of the casing and one section of the socketed portion of the mouthpiece being integral with each other and with the body portion

of the mouthpiece, the other section of said casing and the other section of said socketed portion of the mouthpiece being integral with each other and being hinged to the body portion of the mouthpiece, whereby to provide a member for clamping the cigar or cigarette in place when closed and for releasing the cigar or cigarette

when opened, a finger piece rigid with the inner end of said hinged member, said body portion of the mouthpiece having a notch providing a clearance for said finger-piece when operated to open the hinged member.
